UNITED STATES PATENT OFFICE

ALFRED W. BRUCE, OF NEW YORK, N. Y.

STEAM BOILER

Application filed June 2, 1927. Serial No. 195,888.

My invention relates, generally, to steam boilers of the locomotive type, and particularly, to those of such type as are designed for operation under comparatively high pressures of steam. The object of the invention is to provide a locomotive boiler of such character which will be of strong and simple construction, and adaptable for application in connection with present standard wheel 10 dispositions; the constituent units of which can be readily assembled and separated as conditions of manufacture and renewal or repair may require, and, when assembled, will be rigidly held against displacement 15 from normal connected relation.

The characteristic feature of novelty and utility of my invention, consists in a locomotive boiler in which are combined three cooperating structural elements, to wit: (1) 20 a steam generating member; (2) a heat absorbing member; and (3) a supporting and stiffening member, connecting the steam generating and heat absorbing members. The heat absorbing and steam generating members 25 may be combined with means for effecting independent circulation of water, consecutively, therein.

The improvement claimed is hereinafter fully set forth.

30 In the accompanying drawings; Figure 1, is a vertical longitudinal central section through a locomotive boiler, illustrating an embodiment of my invention; Fig. 2, a vertical transverse section on the line $g-g$ of Fig. 1; Fig. 3, a vertical transverse section, the right hand half being taken on the line $a-a$ of Fig. 1 and the left hand half on the line $b-b$ thereof; Fig. 4, a front view, in elevation; 40 Fig. 5, a partial horizontal section, on an enlarged scale, on the line $c-c$ of Fig. 3; Fig. 6, a side view, in elevation, of one-half of a steam generating member support; Fig. 7, a view, taken similarly to Fig. 1, illustrating 45 a modification of structural detail; Figs. 8 and 9, vertical transverse sections, through the locomotive boiler shown in Fig. 7, on the lines $d-d$ and $e-e$, respectively, of Fig. 7; Fig. 10, a horizontal section, on the line $f-f$ of 50 Fig. 9; and Fig. 11 a fragmental side eleva-

tion similar to Fig. 1 illustrating a modified form of pipe connections.

In the practice of my invention, referring descriptively to the specific embodiment thereof which has been adopted for exemplification herein, and first to Figs. 1 to 6 inclusive, the essential elements of a locomotive boiler in accordance therewith, consist of a steam generating member, indicated, as a unit, by the reference symbol, A; a heat absorbing member, indicated, as a unit, by B, and a supporting and stiffening member, connecting the steam generating and heat absorbing members, and indicated by C. The detailed description of the essential elements above stated, which follows, is made with notice that they may be varied as to structural detail, in the discretion of a constructor skilled in the art, without departure from the spirit and operative principle of my invention.

In the instance herein set forth, the steam generating member, A, comprises a fire chamber, 1, which is of substantially rectangular transverse section, and has its side walls formed of a plurality of water tubes, 3, curved inwardly at their tops and connected to a central water and steam drum, 4. The side water tubes, 3, on each side of the fire chamber, are connected, at their bottoms, to a water drum, 11, located at that side of the fire chamber and extending from the rear to the forward end of said chamber. A grate, of any suitable and preferred known construction (not shown) is located at the bottom of the fire chamber, and fuel is supplied thereto through one or more door openings, 1^a, controlled by a door or doors, in the ordinary manner.

The gaseous products of combustion are delivered from the fire chamber, through a plurality of tubes or flues in a heat absorbing member, B, which adjoins the forward end of the fire chamber, to a smoke box, 10, located forward of the member, B, and escape to the atmosphere through a stack, 10^a, on the top of the smoke box. The ends of the heat absorbing member are closed by a front header, 12, and a rear header, 13, respectively.

The upper central water and steam drum,

4, of the steam generating member, A, extends throughout the length of said member, and communicates, at its forward end, with a steam receiving chamber, 4^e, (one or more) 5 which extends to or near the rear end of the smoke box, 10, and communicates, at its forward end, with a superheater header, 18, from which steam is delivered to the valve 10 chests of the locomotive on which the boiler is installed, the delivery of steam being controlled by a throttle valve, in the ordinary manner. The water and steam drum, 4, also communicates, at its forward end, with a water circulating pipe, 4^c, which extends forwardly to the front header, 12, of the heat absorbing member, B, to which it delivers unevaporated circulating water, in addition to the boiler feed water, which is introduced into the circulating pipe, 4^c, through a longitudinal 20 perforated pipe, 25. The two water drums, 11, at the bottoms of the sides of the fire chamber, communicate, at their forward ends, with the upper part of the rear header, 13, of the heat absorbing member, B, through 25 pipes, 22, indicated in dotted lines in Fig. 1.

The heat absorbing member, B, extends from the forward end of the steam generating member, A, in line longitudinally therewith, to the rear end of the smoke box, 10, and is of 30 substantially similar construction to the "barrel section" set forth in an application for Letters Patent filed by me January 27, 1927, Ser. No. 164,030. As in said application, it comprises a forward header, 12, a rear header, 35 13, a plurality of fire tubes, 3^b, extending through said headers, from the front sheet of the forward header to the back sheet of the rear header, and a plurality of water tubes, 3^c, surrounding the fire tubes, and extending 40 from the back sheet of the forward header to the front sheet of the rear header. This construction, which is not, per se, claimed as of my present invention, provides for the traverse of the gaseous products of combustion through the fire tubes, 3^b, and the circulation of water between the headers, through the water tubes, 3^c, which surround the fire tubes. The feed water of the boiler is supplied to the heat absorbing member, B, 45 50 through a feed pipe, 25, provided with a check valve, in the ordinary manner, and after circulating through the member, B, and being heated therein by the gases of combustion, is delivered therefrom to the lower side water drums, 11, of the steam generating member, A.

The supporting and stiffening member, C, of the boiler, is in the form of a heavy plate 60 of metal, 20, bent into inverted U transverse section, the vertical portions of which are spaced at such distance apart as to stand on opposite sides of the steam generating and heat absorbing members, to which they are secured. The plate, 20, performs the functions of acting both as a stiffening girder and 65 a supporting connector for the members, A

and B, and of constituting a casing or enclosure therefor. As shown in Fig. 1, it extends throughout the entire length of the boiler, but may, if preferred, have its forward terminal in rear of the rear end of the smoke 70 box. It may either be formed in a single plate or in a transversely curved upper section and two vertical lower sections, all provided with longitudinal flanges, 20^a, secured together by bolts and nuts, or other suitable means, the top section being readily removable when desired. 75

In order to provide for expansion under differences of temperature in service, the steam generating member is rigidly secured to the supporting and stiffening member at one end only, in this instance at its forward end, the rear ends of its lower drums, 11, being fitted to slide freely in guides, 23, fixed on supports, 24, which are secured to the side members of the plate, 20, and the main frame members, 2, of the locomotive on which the boiler is applied. A similar means is employed for securing the supporting and stiffening member to the drums, 11, at their forward ends, but here the members 23' are bolted to the drums as clearly shown in Fig. 6. It will thus be seen that the steam generating member A, is firmly secured at both ends to the supporting and stiffening member except that provision is made to provide for the slight relative longitudinal movement of the securing and secured members due to temperature changes. The front header, 12, of the heat absorbing member, may also be fitted to slide in similar guides, and the rear header, 13, in this instance, is secured to the supporting and stiffening member, 20, by bolts, 21, and nuts, 21^a. In the present instance, as shown in the drawings, provision is made for the slight longitudinal relative movement between the supporting and stiffening member C and the heat absorbing member B by supporting the forward end of the heat absorbing member B, upon the rear end of the floor of the smoke box, 10, with the sides of the header 12 sufficiently close to the supporting and stiffening side walls 20 of the member C to prevent any undesirable side play. In the present instance the weight of the forward end of the member B may be relied upon to hold it upon the supporting floor, or as shown in Fig. 1, the structural parts may be so proportioned that no undesirable play will be present between the forward end of the member B (considered in conjunction with its attached parts), and the top of the member C. 110

The construction above described may be modified, without variation of operative principle, or departure from the spirit of my invention, by providing for the separate maintenance of the water circuits of the steam generating member and the heat absorbing mem- 125 130

ber. For this purpose, referring to Fig. 11, the upper central steam and water drum, 4^x, of the steam generating member, A, may be connected, at its forward end, directly with the lower side water drums, 11^x, through the pipes 22^x. Boiler feed water is introduced through pipe 25^x directly into the front header, 12^x, of the heat absorbing member, from which it flows back, through the tubes, 3^x, to the rear header, 13^x, from which it is conducted directly to the forward ends of the lower side water drums, 11^x, through pipe 22^y.

Figs. 7 to 10 inclusive, illustrate a modification of structural detail, embodying the novel characteristic structural and operative features of the steam boiler hereinbefore described, while differing therefrom in the minor particulars that the heat absorbing member, B, is in the form of a plurality of fire tubes, 3^{bb}, enclosed in a cylindrical shell, 3^a, in the usual manner of a boiler barrel, and that the water circuits of the steam generating member, A, and the heat absorbing member, B, are separately maintained, as in the modification last described. The shell, 3^a, of the heat absorbing member, is secured to a flanged throat sheet, 2^x, of the usual form, at the forward end of the steam generating member, A, the flange being secured to the member C by rivets or bolts 2^y to form a gas tight joint thereby enclosing the member A at its forward end within the member C laterally beyond the shell 3^a. The forward end of the shell being secured in place in any preferred or well known manner. The supporting girder plates, 20, may, in this form of the invention, be considerably shortened.

40 The pipe 22^z connects the upper and lower drums of the member A in a similar manner as the pipe 22^x of the previous modified form. The pipe 25, serves as a feed pipe for the member B and the pipe 26 connects the member B with the member A preferably in the manner as shown.

The member A rests at its forward end upon the supports, 27, to which the lower drums are secured as by bolts or otherwise 50 (not shown) in a similar manner and for the same purpose as are the corresponding parts of the other modifications already described, the supports 27 being rigidly secured to the member C. The rear end of the member A is supported upon the depressed supports 28 rigidly secured to the members C, restricting the member A to the desired slight relative longitudinal movement already referred to, and in like manner, as has already been stated, the weight of the member A, or its proximity to the walls of the member C, will insure it against any undesirable relative movement.

While various expediencies have been 60 shown and described for connecting the three

essential members A, B, and C, it will be readily understood that the preferable requirement, as has been previously stated, is that there be rigid connections at certain portions and sliding connections at others, whereby the members A and B will be secured relative to each other and to the member C in a manner to prevent undesirable displacement of the members relative to each other and to the frame, the connections being such however, as will leave the members A and B free to expand to prevent undesirable stresses due to changes in temperature. It is obvious that there are various ways to accomplish this and the present invention is not 70 limited to any particular manner of accomplishing this result.

The substantial advantages of my invention will be obvious to those familiar with locomotive design and construction, in the particulars of providing a boiler which is of such strength as to be safely operative under comparatively high steam pressure; in which the steam generating and heat absorbing members are relieved from all stresses other than those due to steam generation and pressure; and which is adapted for application in locomotives of various standard wheel arrangements, with a general longitudinal or backbone support, which is attachable to, and removable from, independently constructed units, of any suitable and preferred type, thereby expediting and economizing the manufacture of the individual units, and affording the capacity of their assembly into 80 a complete structure, of greater rigidity than 85 boilers of the water tube fire box type.

I claim as my invention and desire to secure by Letters Patent:

1. In a locomotive, the combination of a locomotive frame structure; a steam generating member; a heat absorbing member for heating water, in communication with the steam generating member, said members being structurally independent one of the other; and means connected with the members, constituting therewith a boiler structure preventing relative longitudinal displacement of the members independently of any frame structure connections, said means being connected with the frame structure, to retain said boiler structure against longitudinal displacement relative to the frame structure.

2. In a locomotive, the combination of a locomotive frame structure; a steam generating member; a heat absorbing member for heating water, in communication with the steam generating member, said members being structurally independent one of the other; and means rigidly connected with at least one portion of each of said members, constituting therewith a rigid boiler structure preventing relative longitudinal displacement of the members independently of any frame structure connections, said means being rig- 100 105 110 115 120 125 130

idly connected with the frame structure to retain said boiler structure against longitudinal displacement relative to the frame structure.

5 3. In a locomotive, the combination of a locomotive frame structure; a steam generating member; a heat absorbing member for heating water, in communication with the steam generating member, said members being structurally independent one of the other; and longitudinally disposed tie means rigidly connected with at least one portion of each of said members, constituting therewith a rigid boiler structure preventing relative longitudinal displacement of the members independently of any frame structure connections, said means being rigidly connected with the frame structure to retain said boiler structure against longitudinal displacement relative to said frame structure.

4. In a locomotive, the combination of a locomotive frame structure; a steam generating member; a heat absorbing member for heating water, in communication with the steam generating member, said members being structurally independent one of the other; and means connected with the members on each side thereof, constituting therewith a boiler structure preventing relative longitudinal displacement of the members independent of any frame structure connections, said means being connected with the frame structure to retain said boiler structure against longitudinal displacement relative to the frame structure.

5. In a locomotive, the combination of a locomotive frame structure; a steam generating member; a heat absorbing member for heating water, in communication with the steam generator member, said members being structurally independent one of the other; and longitudinally disposed tie means connected with said members, constituting therewith a boiler structure preventing relative longitudinal displacement of the members independently of any frame structure connections, said means being connected with the frame structure to retain said boiler structure against longitudinal displacement relative to said frame structure.

6. In a locomotive, the combination of a locomotive frame structure; a steam generating member; a heat absorbing member for heating water in communication with the steam generating member, said members being structurally independent one of the other; and longitudinally disposed tie means and transversely directed means secured together constituting combined means to which said members are connected and constituting therewith a boiler structure preventing relative longitudinal displacement of the members independently of any frame structure connections, said transversely directed means being connected with

the frame structure to retain said boiler structure against longitudinal displacement relative to said frame structure.

7. In a locomotive, the combination of a locomotive frame structure; a water tubular steam generating member; a heat absorbing member for heating water, in communication with the steam generating member, said members being structurally independent one of the other; and sheet metal walls, the sheet metal being of sufficient thickness to be selfsupporting, of sufficient length to at least enclose a portion of the sides of each of said members to strengthen, support, and protect same, said walls, members and frame structure being connected together to prevent relative displacement therebetween.

8. In a locomotive, the combination of a locomotive frame structure; a water tubular steam generating member; a heat absorbing member for heating water, in communication with the steam generating member, said members being structurally independent one of the other; and sheet metal walls, the sheet metal being of sufficient thickness to be selfsupporting, of sufficient length to at least enclose a portion of the sides of said members to strengthen, support, and protect same, said walls being connected with said members constituting therewith a boiler structure preventing relative longitudinal displacement of the members independently of any frame structure connections, said walls being connected with the frame structure to retain said boiler structure against longitudinal displacement relative to said frame structure.

9. In a locomotive, the combination of a locomotive frame structure; a steam generating member; a heat absorbing member for heating water, in communication with the steam generating member, said members being structurally independent one of the other; and means rigidly connected to one portion of each of the members constituting therewith a boiler structure preventing relative longitudinal displacement of the members independent of any frame structure connections, said members being supported to permit freedom of longitudinal expansion, due to heat variation, relative to said frame and said means, said means being connected with the frame to retain the members against longitudinal displacement relative thereto.

10. In a locomotive, the combination of a locomotive frame structure; a plurality of transversely directed members connected to the frame; a water tubular steam generating member; a heat absorbing member for heating water, in communication with the steam generating member, said steam generating and heat absorbing members being structurally independent one of the other; and a sheet metal enclosure, the sheet metal being of sufficient thickness to be selfsupporting,

- extending about the sides and top of the steam generating and heat absorbing members to strengthen, support and protect same, said enclosure and transversely directed members constituting combined means to which said steam generating and heat absorbing members are connected constituting therewith a boiler structure preventing relative longitudinal displacement of the steam generating and heat absorbing members independently of any frame structure connections. 70
11. A steam boiler for locomotives comprising a plurality of transverse members adapted to be supported by and secured to the frame structure of the locomotive; a water tubular steam generating member supported on said transverse members; a sheet metal enclosure extending about the sides and top of said generating member, the sheet metal being of sufficient thickness to be self-supporting, enclosing, strengthening, supporting and protecting said generating member, said enclosure and transverse members constituting combined means to which the generating member is connected; a heat absorbing member for heating water in communication with the steam generating member, said members being structurally independent one of the other; and throat sheet means connecting the enclosure with the heat absorbing member positioning the heat absorbing member relative to the steam generating member. 80
12. In a locomotive, the combination of a locomotive frame structure; a water tubular steam generating member; a heat absorbing member for heating water, in communication with the steam generating member, said steam generating and heat absorbing members being structurally independent one of the other; a sheet metal enclosure, the sheet metal being of sufficient thickness to be self-supporting, extending about the sides and top of the steam generating and heat absorbing members, to strengthen, support and protect same; and connections between said members and the sheet metal enclosure, said sheet metal enclosure constituting means for preventing relative longitudinal displacement of the steam generating and heat absorbing members independently of any frame structure connections. 90
13. In a locomotive, the combination of a locomotive frame structure; a water tubular steam generating member; a heat absorbing member for heating water, in communication with the steam generating member, said steam generating and heat absorbing members being structurally independent one of the other; a sheet metal enclosure, the sheet metal being of sufficient thickness to be self-supporting, extending about the sides of the steam generating and heat absorbing members, to strengthen, support and protect same; and 95
14. In a locomotive, the combination of a locomotive frame structure; a steam generating member; a heat absorbing member for heating water, in communication with the steam generating member, said members being structurally independent one of the other; and a wrapper sheet connected with the members, constituting therewith a boiler structure preventing relative longitudinal displacement of the members independently of any frame structure connections, said wrapper sheet being connected with the frame structure, to retain said boiler structure against longitudinal displacement relative to the frame structure. 100
15. In a locomotive, the combination of a locomotive frame structure; a steam generating member; a heat absorbing member for heating water, in communication with the steam generating member, said members being structurally independent one of the other; and a wrapper sheet rigidly connected to one portion of each of the members, constituting therewith a boiler structure preventing relative longitudinal displacement of the members independent of any frame structure connections, said members being supported to permit freedom of longitudinal expansion, due to heat variation, relative to said frame and said wrapper sheet, said wrapper sheet being connected with the frame to retain the members against longitudinal displacement relative thereto. 105

ALFRED W. BRUCE.
